REVOLVER COTTON-MERCERIZING MACHINE.

1,038,152.

Specification of Letters Patent. Patented Sept. 10, 1912.

Application filed June 3, 1909. Serial No. 499,948.

To all whom it may concern:

Be it known that I, JOHANNES KLEINEWEFERS, manufacturer, a subject of the King of Prussia, residing at Krefeld, in the German Empire, have invented a new and useful Revolver Cotton-Mercerizing Machine, of which the following is a specification.

My invention relates to improvements in revolver cotton mercerizing machines, according to which the revolver system for cotton mercerizing machines is arranged in horizontal position, around a vertical main axle.

A machine conforming to the present invention differs from all the known machines in the rollers being supported horizontally and all the driven ones converging to the center of the machine. The other rollers remaining parallel to the driven ones are mounted on crank shafts, and thereby all the rollers can be supported twice in a single common casing. By doing so the machine becomes as stable as necessary and the rollers are so secured that they are able to stand the tension necessary to the mercerization process without nipping or deflecting. The whole arrangement of the mechanism is also more simple, and the parts are more easily accessible.

With this new machine each single operation, the treatment with lye, the squeezing and washing, the taking up and off of the hanks takes place in the same horizontal plane, whereby the intermixture of the liquors is avoided. This arrangement has the further advantage of providing a treatment of the hanks with acid, as each tank is separated and used only for one purpose and not at one time for the treatment with lye and at another time with acid. The horizontal position of the hanks is of great efficiency in all operations as a large surface of the hanks is presented always to the lye without the rollers dipping too much in the lye, and without the lye being soiled by the lubricant of the rollers. In the vertical machines having rollers one above the other the lower roller has to be positioned entirely in the lye in order to dip the same amount of yarn, whereby the oil of the roller bearings may spoil the lye. A great advantage is also obtained at the washing period by the great surface the hanks present to the

flowing water and thus this operation is very efficient. Another thing may also be mentioned here as it constitutes a main part of this invention. A special driving mechanism for the revolver is not necessary according to the new arrangement, as the mechanism driving the rollers also turns the revolver at the end of each single operation automatically.

The object of the invention will more fully appear in the following specification taken in connection with the accompanying drawings, in which—

Figure 1 is a vertical section on the line $\alpha-\alpha$ of Fig. 4, Fig. 2 is a vertical view in elevation, Fig. 3 is a plan view of cam disk 35, Fig. 4 is a plan view of the machine, 70 Fig. 5 is a detail view of the squeezing apparatus, Fig. 6 is a detail view showing the roller adjusting mechanism, Fig. 7 is a front view of the mechanism shown in Fig. 6.

The machine is shown as having 6 pairs 75 of rollers shown in Fig. 4 as 1-6. In this arrangement the treatment of the several hanks of yarn is carried out by a full revolution of the revolver. When the pair of rollers are at position 1 the treated material 80 is taken off and the fresh charging occurs, which is treated in the positions 2 and 3 with lye, and in position 4 the lye is removed from the cotton by squeezing it with rollers. Then in position 5 the yarn is cleaned by 85 means of washing in warm water and a neutralization follows in a bath mixed with sulfuric acid. In position 6 at first it is washed with cold water and then dried by squeezing rollers to such a degree, that after 90 advancing to position 1 the material has become nearly dry and may be taken off.

To carry out the process of mercerization the cotton is placed upon a pair of horizontal rollers 7, 8, of which 7 is driven from 95 the main shaft 9 and pulley 10 by means of the bevel gear wheels 11 and 12, the gears 13, 14, 15, 16 and the bevel gear wheel 17, which acts upon the six conical wheels 18, mounted on the shafts 19 of the rollers 7, 100 see Fig. 1. The shafts 19 carrying the rollers 7 are supported in two bearings 21, 22 of the casing 20 inclosing also the shaft 23, which serves to turn the revolver after each 105 operation of the rollers and therewith to change the position of the same. The rollers

8 are driven by the rollers 7 through the tension of the cotton hanks only and, as the hanks vary in length, the distance between the rollers 7 and 8 has to be regulable. For this purpose the rollers 8 are pivotally mounted on crank shafts 24, the bearings 25 and 26 of which are fixed in the casing 20. Consequently if the revolver revolves, the rollers 7 and 8 move with it and remain at 10 the same distance from one another.

To the journal 27 of each crank shaft 24 the hub of a lever 28 is fast to which in turn a lever 29 is pivotally mounted at 30, the lever 28 having an extension 31 projecting 15 into the recess 32 of the forked lever 29 and guided by it, and connected by a set screw 33 loosely connected in the arm 28 and lever 29 to alter the distance between both and thereby the distance between the roller 7 20 and 8 at the charging period. To the lever 29 is secured a roll 34 which is guided in and by a curved disk 35 mounted on the frame 36 and pressed to it by the weight of the roller 8 (see Fig. 4). The curved disk 25 35 is provided with a downwardly inclined extension 37 and the roll 34 following the path in the curved disk will oscillate about the pivot 30, taking with it the lever 28 and moving the roller 8 toward the roller 7 and 30 then in the opposite direction. In the position 1 shown in the Fig. 4 the rollers 7 and 8 have their shortest distance because the roll 34 belonging to the respective lever 29 is in the outmost curve of the guiding disk 35; 35 taking off and feeding the cotton on to the rollers may be done easily. When the revolver is rotated and the newly charged rollers 7, 8 are approaching the position 2, the distance of the rollers becomes increased 40 by lever 30 being forced inwardly by the roll 34 following the path of the curve in the cam disk to such a degree that the hanks have the required tension when the rollers have reached position 2. The cotton hanks 45 having different lengths when fed on to the rollers are requiring their adjustment and for this purpose the set screw 33 is used.

To bring the roller pairs in the different positions 1-6 and allow the necessary time 50 to perform their respective functions the revolver is rotated intermittently by the following means: From the main shaft 9, the gear 16 is driven by the intermediate gears 11, 12, 13, 14 as hereinbefore described, and 55 the conical wheel 17 connected with the gear by screws or other means engages the conical wheels 18 operating the rollers 7. The shaft 23 and the casing 20 connected with it by a bolt 84 are rotated by the gear 16 when released to do so because the rollers offer more 60 resistance due to the great tension of the cotton hanks and therewith to the high axial pressure in the bearings to their respective movement than the whole revolver, espe-

cially in view of the fact that the casing 65 or turn table 20 is provided with wheels 38 running on a suitable path 39 of the frame 40 which facilitates its movement. Therefore the turn table has to be locked when the rollers are in the operating position and 70 this is done by a locking pin 41 in a casing 42 which released to the action of the spring 43 enters one of the six equidistant notches 44 provided in the casing 20 corresponding to the six different positions of the rollers. 75 To draw back the locking pin 41 out of the notches and of the way of the revolver, on the rod 45 of the locking pin 41 one end of a lever 46 is fixed, supported in a bracket 47 of the casing 42. From the main shaft 80 9 by means of a worm 48 and worm wheel 49 and the shaft 50, a cam disk 51 mounted thereon is driven, the cam 52 of which acts on the hooked end 53 of the lever 46 thereby rocking it and removing the locking pin 41 85 out of the notch 44, releasing the revolver to revolve until the locking pin enters the next notch or guide hole. After each revolution of the cam disk 51 the revolver makes $\frac{1}{6}$ of a revolution, the conical wheels driving 90 the rollers 7 are put in rest and the locking pin 41 rides idly upon the edge of the casing until it is caught again at the next guide hole 44 whereby the revolver is locked and the rollers rotating perform their proper 95 function.

As mentioned hereinbefore the impregnation of the cotton hanks with lye is effected at position 2 and 3 of the rollers. As may be seen from Fig. 2 the tanks have to be lowered to allow the rollers to pass by each movement of the revolver. For this purpose the tank 85 is provided with a beveled surface 54, on which small wheels 55 mounted in advance of each roller set on the casing or turn table 20 move forward when the revolver revolves, thereby pressing the tank down and giving the roller pair the path free. The tank is held in and returned to its normal position by any suitable means. 100 Arrangements in any well known manner are also made to lead back the used lye to the receiving tank while fresh lye flows in. Care is thus taken to secure sufficient impregnation especially as all the under part 105 of the hanks is in the lye and, as already said, a large surface is presented to it. To press out the lye at position 4 a pinching or squeezing roller 63 is provided mounted on angle levers 64 (Fig. 5) the other ends of 110 which are engaged by the rods 65 surrounded by compression springs 66, one end of which bear against brackets 67, the other against collars 68 on the rods. Any lye remaining in the cotton hanks is removed by washing in 115 warm water at position 5, whereas at position 6 a further washing and the neutralization by treating with acid occurs. Flowing 120 125

in of the washing liquids has to be regulated and this is done by the curved cam disk 51 (Fig. 4), having curved grooves 69 by which the levers 70 and 71 are operated. The lever 70 forms a bell crank lever with the two-armed lever 72, the arms of which are connected with links 73 and 74 with the levers 75 and 76, controlling in a well known manner the valves 77 and 78. These valves govern the inflow of the liquids to the pipes 79 and 80 of which pipe 79 leads warm water and the pipe 80 acid for neutralization. The cotton hanks having reached position 6 are again washed, but with cold water the inlet valve 81 being controlled in the same manner through the cam disk 51 by the lever 71 as the valves 77 and 78 described heretofore. From the pipe 83 the cotton hanks become watered and thoroughly washed and then dried by a squeezing device like at position 4 (see Fig. 5).

It is obvious, that another pair of rollers may be interposed between the fourth and fifth roller pair, where the cotton hanks may be pinched or squeezed again and at the same time damped or steamed by water. In this manner the lye is extracted in the highest possible degree. The necessary devices for this purpose may be arranged as at 5 or 6.

30 I claim:

1. A machine for mercerizing cotton comprising a turn table, a pair of rollers rotatably mounted thereon and adapted to hold the material to be operated upon, a gear wheel mounted upon one of said rollers, a gear wheel meshing with said first gear wheel, means for rotating said second gear wheel to cause rotation of said table and means acting intermittently to check the rotation of said table, whereby the roller will be rotated, said material preventing rotation of the roller when said checking means is in its inoperative position.

2. In a cotton mercerizing machine, in combination, a turntable, means for rotating the same, a pair of rollers supported by said turntable and upon which the material to be treated is carried, a tank adapted to contain liquid in which the material to be treated is adapted to be immersed, and means for moving said tank up and down with respect to the rollers, whereby it may occupy operative or inoperative positions with respect to the material carried by the rollers.

55 3. In a cotton mercerizing machine, in combination, a turntable, means for rotating the same, a pair of rollers supported by said turntable and upon which the material to be treated is carried, a tank adapted to contain liquid in which the material to be treated is adapted to be immersed, means normally holding said tank in operative position with respect to the rollers, and means for depressing the tank as the rollers approach and leave the same, whereby it will

be moved out of the path of the rollers, said means being inoperative when the rollers are in registry with the tank, whereby it will assume its operative position.

4. In a cotton mercerizing machine, in combination, a turntable, means for rotating the same, a pair of rollers supported by said turntable and upon which the material to be treated is carried, a tank adapted to contain liquid in which the material to be treated is adapted to be immersed, means normally holding said tank in operative position with respect to the rollers, and means carried by the turntable for depressing said tank.

5. In a cotton mercerizing machine, in combination, a turntable, means for rotating the same, a pair of rollers supported by said turntable and upon which the material to be treated is carried, a tank adapted to contain liquid in which the material to be treated is adapted to be immersed, means normally holding said tank in operative position with respect to the rollers, and means carried by the turntable in advance of said pair of rollers for depressing said tank.

6. In a cotton mercerizing machine, in combination, a turntable, means for rotating the same, a pair of tank bearing rollers carried thereby, said rollers being in the same horizontal plane, and automatic means for moving one of said rollers in a direction at right angles to its longitudinal axis only, whereby the distance between said rollers will be varied.

7. In a cotton mercerizing machine, in combination, a turntable, means for rotating the same, a pair of hank bearing rollers carried thereby, said rollers being in the same horizontal plane, means for adjusting the position of one roller with respect to the other, and automatic means for moving one of said rollers in a direction at right angles to its longitudinal axis only, whereby the distance between said rollers will be varied.

8. In a cotton mercerizing machine, in combination, a turntable, means for rotating the same, a pair of hank bearing rollers carried thereby, said rollers being in the same horizontal plane, and automatic means for moving one of said rollers in a lateral direction only, whereby the distance between the rollers will be varied, said roller being free from movement in the direction of its longitudinal axis.

9. In a cotton mercerizing machine, in combination, a turntable, means for rotating the same, a pair of hank bearing rollers carried thereby, said rollers being in the same horizontal plane, a crank for supporting one of said rollers, and means for automatically rotating said crank, whereby the distance between the rollers will be varied.

10. In a cotton mercerizing machine, in combination, a turntable, means for rotating the same, a pair of hank bearing rollers car-

ried thereby, said rollers being in the same horizontal plane, a crank for supporting one of said rollers, a cam, and means connected to said crank and operatively engaging said cam to automatically rotate said crank, whereby the distance between the rollers will be varied.

In witness whereof, I have hereunto signed my name in the presence of two subscribing witnesses.

JOHANNES KLEINEWEFERS.
